(57) **CLAIM**

The ornamental design for a combined flashlight and stun gun, as shown and described.

DESCRIPTION

FIG. 1 is a perspective view of a combined flashlight and stun gun, showing our novel design;

FIG. 2 is a top view thereof;

FIG. 3 is a bottom view thereof;

FIG. 4 is a right side view thereof;

FIG. 5 is a front view thereof;

FIG. 6 is a left side view thereof; and,

FIG. 7 is a rear view thereof.

The broken lines in FIGS. 1–7 represent unclaimed portions of the combined flashlight and stun gun, and form no part of the claimed design.
